DESIGN FOR A BATH MITT

Apollonia M. Schroeder, Kansas City, Mo.

Application August 17, 1938, Serial No. 79,401

Term of patent 14 years

To all whom it may concern:

Be it known that I, Apollonia M. Schroeder, a citizen of the United States, residing at Kansas City, in the county of Jackson and State of Missouri, have invented a new, original, and ornamental Design for a Bath Mitt, of which the following is a specification, reference being had to the accompanying drawing, forming a part thereof.

Fig. 2 is an end elevation of the same; and Fig. 3 is an edge view of the bath mitt.

The front of the bath mitt is plain and without ornamentation.

I claim:

The ornamental design for a bath mitt, as shown and described.

APOLLONIA M. SCHROEDER.
